UNITED STATES PATENT OFFICE.

CHARLES RAYMOND DOWNS, OF NEW HAVEN, CONNECTICUT, ASSIGNOR TO WEISS AND DOWNS, INC., OF NEW YORK, N. Y., A CORPORATION OF NEW YORK.

PROCESS OF CRACKING PETROLEUM HYDROCARBONS.

Application filed December 1, 1925. Serial No. 72,422.

In a copending application, Serial No. 692,223, filed February 12, 1924, I have disclosed the use of boiling sulphur as a method of heating bituminous materials such as tars or petroleums or their distillates in such a way that distillation will take place with the least amount of superheating and cracking. This process was based on the fact that the use of a boiling liquid as a heating means, especially where the heat transfer takes place through the medium of condensation of the vapors of the boiling liquid, gives a high rate of heat input without a large temperature differential.

In the petroleum industry much use is made of the type of distillation, destructive in character, which is known as cracking. This involves the subjection of selected fractions of the oil to such temperatures as will decompose them into lighter hydrocarbons, preferably of the gasoline type. In these processes the control of the temperature of the oil being cracked is important as it must be high enough to enable decomposition to take place but not so high as to cause further decomposition into excessive amounts of permanent gases, aromatic hydrocarbons, tar, etc.

The invention herein described comprises the extension of the principle described in Serial No. 692,223 to cover the use of boiling sulphur as a means of heating in processes designed for the "cracking" distillation of petroleum products. These are of many various types and I do not confine myself to the application of the boiling sulphur heating means to any one type. Those processes in commercial use to-day operate most efficiently over a range of temperature from 750° F. to 950° F., or thereabouts, the optimum temperature for any specific case varying with the particular oil fraction being treated, the nature of the crude petroleum from which it was obtained, the pressure under which the operation is carried on, etc.

Over this range of temperature, sulphur with a boiling point at sea level of 832° F. can be made to maintain a constant and uniform temperature by regulation of the pressure on the sulphur system, being varied above, at or below atmospheric pressure, according to the particular temperature desired. In general, the use of absolute pressures between 9 lbs. and 50 lbs. per sq. in.

gives a sufficient range for practical operation. The use of the latent heat of condensation of sulphur vapor as a heat supply renders it possible to obtain high rates of heat flow without high temperature differentials, thereby enabling the cracking temperature to be maintained at the optimum point desired, without the possibility of excessive temperatures and further decomposition into undesirable products.

In order to describe the invention I give the following example accompanied by the drawing which is diagrammatic only. The example is for illustrative purposes only and I do not intend to limit myself thereby.

Numerical 1 represents a sulphur boiler. The boiler is set in a furnace 2 with firebox 3 and exit 4 to a stack (not shown) to allow the escape of the combustion products. The boiler connects by a pipe 5 to a jacket 6 containing the oil heating element 7 which may, for example, be a pipe coil. The jacket 7 connects by a pipe 8 to a pressure regulating tank 9 with gauge 10 and pipe 11 for the introduction of an inert gas from a pump or other pressure source.

In operation, the oil to be cracked enters in the direction of the arrow at 12 and if desired may pass through a preheating coil 13 set in the cooler portion of the furnace 2, or be preheated in any other convenient way. It then passes to the coil 7 in the sulphur heating jacket 6 and exits in the direction of the arrow at 14 discharging to condensers, reaction chambers, pressure reducing valves, vapor boxes, bubble towers, or whatever device is used in the particular cracking system to which this heating means is applied. Sulphur is boiled in the boiler 1, the vapors passing by the pipe 5 to the jacket 6 where by condensing they give up their heat to the oil passing through the coil 7. The condensed sulphur returns through the pipe 5 to the boiler 1. By maintaining a suitable inert gas pressure on the tank 9, the boiling point of the sulphur may be fixed at a predetermined point, above which the oil in the pipe 7 cannot be heated. The tank 9 is not essential to the invention as the jacket 6 may carry a pressure gauge and inert gas from a pressure source applied directly to the jacket. In this process the vapors of the sulphur do not come into direct contact with the oil to be heated but are separated from it by metal or other ma-

terial through which the heat transfer takes place.

The boiler used may be of any type, the heating of the oil may be in containers other than coil-shaped and, in general, I do not intend to limit myself in any way by the specific details of the construction shown. It is my intention to cover broadly the use of boiling sulphur or condensing sulphur vapor as a means of heating oils of any kind, but more especially petroleum oils to a temperature suitable for cracking the oil. The oil cracking itself may be carried on at, above or below atmospheric pressure, depending on the particular cracking system to which my method of heating is applied.

Having described my invention, I claim:

1. In cracking petroleum products, the step which comprises heating them by means of the vapors of boiling sulphur out of direct contact therewith but in heat transferring relation thereto and regulating the

temperature of the said sulphur vapors by the pressure applied thereto.

2. In cracking petroleum products, the step which comprises heating them by means of the vapors of boiling sulphur out of direct contact therewith but in heat transferring relation thereto and regulating the temperature of the said sulphur vapors by the pressure applied thereto by means of a neutral fixed gas.

3. In cracking petroleum products, the step which comprises heating them by means of the vapors of boiling sulphur out of direct contact therewith but in heat transferring relation thereto and regulating the temperature of the said sulphur vapors by the pressure applied thereto by means of a neutral fixed gas at greater than atmospheric pressure.

In testimony whereof, I hereby affix my signature.

CHARLES RAYMOND DOWNS.
